SPRAY PAINTING APPARATUS
Harland V. Veum, Whittier, Calif., assignor to
Edwards S. Sawyer, Eugene, Oreg.
Filed Oct. 1, 1962, Ser. No. 227,473
11 Claims. (Cl. 239—126)

This invention relates in general to spray painting, and more particularly to apparatus for direct spray application of coating compositions to surfaces without employment therewith of compressed air or the like gases. Some of the coating compositions which can be applied in accordance with this invention include materials which may be more specifically defined as varnishes, vinyls, lacquers, enamels, plastics, and the like, as well as texture and acoustic materials and those generally termed "paint."

Heretofore and at the present time, compressed air is generally employed through suitable nozzle devices as the means for atomizing the coating material and directing the resultant finely divided spray toward the working surface to be coated. For such purpose, relatively large volumes of air at pressures of from approximately 40 to 80 lbs. per square inch are usually required. Even under the best of such conditions, it is necessary to use not only relatively large volumes of air, but also relatively large proportions of thinners or solvents in most of the coating materials in order to reduce the viscosity sufficiently and otherwise modify the fluid characteristics of the coating composition such that it will flow to the nozzle device at the proper rate and interact with the air stream to form a finely divided spray of adequate solidity, volume, and form.

Such combined requirements for both relatively large volumes of spray air and solvent thinners have a number of disadvantages. First, the relatively large proportion of thinner or solvent required to be used greatly increases the total initial cost of the coating material. Secondly, because of the relatively large volume and high velocity of the air associated with such conventional air spray devices, a considerable proportion of the coating material in and surrounding the spray is propelled in the form of a light, fog-like stream, and because such air stream obviously cannot penetrate the working surface toward which it is directed, but must be largely deflected before reaching such surface, the fog of coating material is thereby likewise deflected by the deflected air stream from the course of the spray and never impinges upon the working surface. A large percentage of the coating material is thus carried away and dissipated in the surrounding air in the form of a fine dust. Thirdly, the cooling effect resulting from release of the spray air undesirably cools the coating composition and tends to cause condensation of water vapor both within the spray and on the surface to which the spray is applied, which is detrimental to the quality and appearance of the resultant coating.

Additionally, the continuous requirement for large volumes of pressure air represents an appreciable power demand, which is inherently inefficiently utilized and which further adds to the cost of the coating operations. Furthermore, the conventional air spray method of coating the interior of relatively small enclosures or containers is impractical in many cases, as those experienced in the art will appreciate.

Attempts heretofore made to eliminate the use of compressed air in connection with so-called spray painting have been unsatisfactory for a number of reasons, among them being the practical difficulties of applying sufficient pressure to and successfully pumping the kind of fluids or semi-plastic coating compositions involved. The fluid handling, pumping, and controlling equipment heretofore employed has been subject to operational difficulties and

2

rapid wear and deterioration. Among the operational difficulties encountered has been the lack of uniformity and control of the pressures involved, when apparatus of otherwise practical design has been used. By this is meant that when relatively high speed pulsationless types of high pressure pumping equipment is attempted to be used, it is found to be extremely unsuited to the intermittent handling of relatively small quantities of viscous and sometimes abrasive coating compositions. On the other hand, when relatively low speed pumping equipment, such as conventional reciprocating pumps are used, which are more suited for handling these materials, relatively high amplitude pressure pulsations and non-uniform pressures usually result. Contributing largely to such difficulties are the requirements for the pumping equipment to handle intermittently a relatively low and extremely variable volume of viscous coating material at relatively high pressure. Also, such systems were heretofore very difficult, if not impracticable to clean up, that is, to purge all the relatively complicated internal parts after use.

It is, therefore, an object of this invention to eliminate the hereinbefore mentioned difficulties and disadvantages heretofore associated with conventional spray coating methods and apparatus.

It is an object of this invention to furnish a spray painting system which generally raises the efficiency of transfer of the coating compositions to the working surfaces to be coated.

It is another object of this invention to furnish a spray painting system, in which the requirements for use of thinners in the coating compositions is minimized together with the attendant reduction in cost.

It is another object of this invention to supply a spray coating system, in which the use of compressed air is eliminated, thereby eliminating the waste of coating composition inherently associated with such use of compressed air.

It is still another object of this invention to present a spray painting system of increased efficiency and in which the power requirements for its operation are reduced.

It is a further important object of this invention to furnish a coating composition pumping and pressurizing system, which has superior operating characteristics in regard to accurate control of output pressure and freedom from pressure variations and pulsations.

It is also an object of this invention to furnish a so-called spray painting system as aforesaid, in which the apparatus is more durable and troublefree.

The objects of this invention are in general attained by a system, in which the use of compressed air or the like gas is completely eliminated and high pressurization of the coating composition itself is solely employed for atomizing and forming the coating material spray. The objects are also attained by the use of fluid pressurization means, which is of improved efficiency and in which the working parts are of relatively slow or low velocity in so far as its relation to or contact with the coating composition is concerned, combined with novel and improved control means for maintaining the output of such pressurization means at a constant pressure, free from pulsations.

These and other objects, advantages, and features of novelty will be evident hereinafter.

In the drawings, which illustrate a preferred embodiment and mode of operation of the invention and in which like reference characters designate the same or similar parts through the several views:

FIGURE 1 is a view partly diagrammatic and partly in longitudinal section of the general assembly of the apparatus and illustrating one stage of its operation.

FIGURE 2 is a view of a fragmentary portion of the apparatus of FIGURE 1 and illustrating another stage of its operation.

FIGURE 3 is an enlarged detail rear elevational view of a portion of the valving apparatus of FIGURES 1 and 2.

Apparatus

Referring mainly to FIGURE 1 of the drawings, for convenience of description the apparatus may be considered as comprising two main portions, namely, the oil pressurizing and actuating system shown within the dotted enclosure A, and the coating composition pressurizing and circulation system shown within the dotted enclosure B.

Referring first mainly to the aforesaid oil pressurizing and actuating system apparatus shown within the dotted enclosure A, an oil reservoir is shown at 10 for containing a suitable quantity of oil or the like hydraulic fluid for supply to the system. The suction inlet connection of a positive displacement pump 12 is connected through pipe 14 to a filter 16 which is submerged in the body of oil 18 within the reservoir 10. The discharge of pump 12 is connected through pipes 20 and 22 to an inlet-outlet connection 24 in the bottom of an accumulator 26 which is preferably of the conventional bladder type. The oil pressure line 28 and accumulator 26 are, in turn, connected through pipe 28, pressure regulator 30, and branch pipe 32 to the pressure inlet port connection 34 of a four-way, rotary pilot valve 36. The oil pressure line 28 and accumulator 26 are also connected by way of pipe 28, pressure regulator 30, and branch pipe 40 to the pressure inlet 42 of a four-way, piston type control valve 44, the construction and operation of which is described hereinafter.

The discharge or exhaust connection 46 of the control valve 44 is connected by way of return lines 48 and 49 to return pipe 50 which enters the oil reservoir 10. The discharge or exhaust connection 52 of the before mentioned four-way pilot valve 36 likewise makes return connection through lines 54 and 49 to the return pipe 50 which enters the oil reservoir 10. An automatic pressure relief, unloading valve 56 and a manually operable bypass valve 58 interconnect the oil pump pressure discharge line 20 with the return line 49. A pressure gauge 47 is connected through pipe 51 to the oil pressure line 40.

The four-way control valve 44 is constructed with an elongated inner bore 60, which contains three axially spaced apart cylindrical valve spools 62, 64, and 66 interconnected for simultaneous axial movement within the bore 60 by a common axial piston rod 68, one end of which extends outwardly through an end thereof and into a pilot cylinder 70 wherein it is connected to a pilot piston 72. Opposite internal ends 74 and 76 of the pilot cylinder 70, on opposite sides of the piston 72, are connected through pipes 78 and 80, respectively, to opposite port connections 82 and 84 of the four-way pilot valve 36.

The bore 60 of the control valve 44 is provided with five annular axially spaced apart ports, namely, an outermost pair of exhaust ports 88 and 90, an inner, opposite pair of pressure inlet and outlet control ports 92 and 94, and a central pressure inlet port 96. The before mentioned pressure line 40 makes connection at 42 with the said pressure inlet port 96, as before mentioned. The exhaust ports 88 and 90 are connected through a common internal manifold passage 100 with the before mentioned exhaust connection 46 which is, in turn, connected through pipe 48 and line 49 to return connection 50 to the oil reservoir 10, as before described.

The inlet and outlet ports 92 and 94 of the control valve 44 make connection respectively through pipes 102 and 104 with inlet connections 106 and 108, which lead through internal head passages 110 and 112 to the opposite internal ends 114 and 116 of a relatively large hydraulic actuating cylinder 120. The actuating cylinder 120 contains a piston 122 attached to the inner end of a piston rod 124, which extends outwardly through a packing gland 126 in the rod end of the hydraulic cylinder for connection with the piston rod of an opposite pressurizing cylinder, as hereinafter more fully described.

Referring next primarily to the before mentioned coating composition pressurizing system apparatus shown within the dotted enclosure B of the drawings, the pressurizing cylinder previously referred to is shown at 130.

- 5 The pressurizing cylinder 130 contains in its bore a piston 132 connected to the inner end of a piston rod 134 which, in turn, passes out through the rod end of the cylinder through a packing gland 136 and makes coaxial coupling at 138 with the before mentioned piston rod 124 extending from the piston 122 of the actuating cylinder 120. Opposite inner ends 140 and 142 of the pressurizing cylinder 130 on opposite sides of the piston 132 make connection by way of internal head passages 144 and 146, respectively, to exterior connections 148 and 150.
- 10 A coating composition feed and circulation pump 152 has its inlet connection 154 connected through suction pipe 156, filter 158 to a flexible suction hose 160, the inlet end 162 of which is adapted to be placed in a body of coating material, as shown at 164 contained within a suitable container, such as a can or drum 166.
- 15 The discharge 168 of the feed pump 152 is connected through pipe feed 170 and thence through opposite check valves 172 and 174 and manifold feed pipes 176 and 178 to the before mentioned connection inlets 148 and 150, respectively, at opposite ends of the pressurizing cylinder 130. The check valves 172 and 174 act in the manner indicated by the arrows shown thereon to permit the coating composition to flow therethrough to the opposite ends of the cylinder in the directions indicated by the arrows, but to prevent flow therethrough in the opposite directions. The discharge line 170 of the pump 152 is also connected by way of manifold pipe 180 to an adjustable back pressure relief valve 182 which, in turn, is connected through a return pipe 184 to a flexible hose 186, the opposite end of which is, in turn, adapted to be placed within the before mentioned container 166 for return and recycling of coating composition from the feed pump, as hereinafter described. For convenience, the flexible suction hose 160 and return hose 182 may be mechanically attached together by suitable clip means 188.
- 20 The before mentioned connections 148 and 150 of the pressurized cylinder 130 are also connected respectively through check valves 190 and 192 to a discharge line 194 provided at the end thereof with a hose connection 196. In operation, spray gun, as illustrated generally at 200, is connected through a suitable high pressure hose 198 to the hose connection 196 from which it receives its supply of pressurized coating composition. The coating composition discharge line 194 is also connected through a pipe 202 to a pressure accumulator 204 adapted to contain a volume of entrapped air for the purpose of smoothing out pulsations and maintaining a relatively uniform pressure of the coating composition fed to the spray gun 200.
- 25 The oil pressurizing pump 12 and the coating composition feed pump 152 are drivingly connected through separate belt drives 206 and 208, which extend respectively between pulley 210 on the drive shaft of pump 12 and pulley 212 on the drive shaft of the feed pump 152 and pulley 214 on the shaft of a suitable prime mover, such as a gasoline engine, as indicated at 216.
- 30 Extending laterally from the coupling 138, which interconnects the piston rods 124 and 134 of the cylinders 120 and 130, respectively, is a flange member 220. Mounted adjacent the flange member 220 intermediate the confronting ends of the cylinders 120 and 130 on a parallel guide member 222 is an axially reciprocable sleeve 224. The sleeve 224 is provided with annular stop flanges 226 and 228 on opposite ends thereof, which are positioned to be engaged by flange 20 adjacent the opposite limits of reciprocation of the piston rods 124 and 134 as a unit, thereby to shift the sleeve 224 axially on the guide member 222 within predetermined axial limits. Extending from an intermediate portion of the sleeve 224 is a control arm 230, the outer cylindrical end of which engages the

groove formed between opposite radial fingers 232 and 234 forming the outer end of a forked lever 236. The opposite end of lever 236 is fixed to a shaft 238, which extends into the interior of the four-way control valve 36 and is coupled to the interior plug valve portion thereof shown at 240, for rotation of such plug valve portion 240 between valving limits, as hereinafter specified. The plug portion 240 of the control valve 36 is provided with a pair of diametrically opposite passages 242 and 244 adapted to perform a valving interconnecting action between the several control valve ports and connections 52, 82, 34, and 84, as hereinafter more fully described in connection with the operation of the apparatus.

Operation

To initiate the operation of the hereinbefore described spray system, the bypass valve 58 is first opened, after which the engine 250 is started which drives both the oil pump 12 and the coating composition feed pump 152. The oil pump 12 withdraws oil from the reservoir 10 through the filter 16 and suction pipe 14 and discharges it into the pressure line 20 and thence through the opened bypass valve 58 and return through pipes 49 and 50 to the oil reservoir. After the oil pump 12 has thus been put into operation, the bypass valve 58 is closed, and immediately thereafter, in the absence of a demand for discharge of coating composition from the spray gun 200, the oil pressure in the pressure line 20 builds up to a value determined by the adjustment of the unloading bypass valve 56. The unloading valve 56 is then adjusted until the desired pressure is maintained in the pressure line 20. The oil pump 12 and the unloading valve 56 are preferably such that a substantially constant pressure of 2200 lbs. may be maintained in the pressure line 20.

The pressure in line 20 and oil therein is transferred through pipe 22 to the accumulator 26 in sufficient quantity to bring the pressure in the accumulator 26 up to the same pressure as that existing throughout line 20. This oil pressure is communicated through pipe connection 28 to the pressure regulator valve 30 and thence through one branch pipe 32 to the pressure inlet port connection 34 of pilot valve 36, and through the other branch pipe 40 to the pressure inlet 42 of the pilot operated control valve 44, both at a suitable pressure determined by the pressure regulating valve 30 and as indicated by the pressure gauge 47 in accordance with the pressure requirements of the particular coating composition to be applied to the spray gun 200. Normally, for most coating compositions, the regulator valve 30 is adjusted to give an oil pressure in pipes 32 and 40 in the order of 50 to 2200 lbs. per square inch.

Assuming the pilot valve 36 initially to be in the position shown in FIGURE 1, oil is transferred under pressure through branch pipe 32, inlet port connection 34, valve passage 244, port connection 84, and pipe 80 into the end 76 of the pilot cylinder 70, and the opposite end 74 of the pilot cylinder 70 is connected through pipe 78, pilot valve port connection 82, pilot valve passage 242, pilot valve port connection 52 to pipe 54 and thence through return pipe lines 49 and 50 to the oil reservoir 10. Under the latter conditions, the piston 72 in the cylinder 70 is immediately forced to the extreme left hand position, and thereby moves the valve spools 62, 64, and 66 within the bore 60 of the control valve 44 likewise to their extreme left hand positions, all as shown in FIGURE 1. In this latter position of the valving mechanism of the control valve 44, the oil under pressure, which flows through the pressure regulator 30, is free to flow through branch pipe 40, control valve pressure inlet 42, valve port 96, and thence through the opening interval between valve spools 64 and 66 and out through port 94, pipe 104, through cylinder connection 108 and passage 112, into the right hand end 160 of the actuating cylinder 120. At the same time, the left hand end 114 of the actuating cylinder 120 is put into communication with

the coil return exhaust lines 49 and 50 by way of passage 110, cylinder connection 106, pipe 102, valve port 92, and through the open interval intermediate the valve spools 62 and 64 to the manifold passage 100, valve exhaust connection 48, and pipe 46.

The differential pressure thus applied across the piston 122 in the actuating cylinder 120 tends to move it in a left hand direction, as indicated by arrow 118, thus also tending to move the piston rods 124 and 134 and the piston 132 in the pressurizing cylinder 130 in the direction indicated by arrow 118. Such motion will be intermittent and at relatively slow rate depending upon the occurrence and rate of demand for coating composition from the pressurizing cylinder 130, as controlled by the spray gun 200. When the piston rod assembly has moved in the left hand direction, as indicated by the arrow 118, sufficiently far to bring the flange 220 carried by the coupling 138 into engagement with the stop flange 218 on the left hand end of sleeve 224, the arm 230 carried thereon will engage the finger 234 and thereby cause the valve lever 236 to be moved, such as to rotate the central plug portion 240 of the pilot valve 36 in a counterclockwise direction from the position shown in FIGURE 1 to the position shown in FIGURE 2, or as illustrated in FIGURE 3, from the position shown in solid lines to the position shown in broken lines.

With the plug portion 240 of the pilot valve 36 thus positioned, as shown in FIGURE 2, the oil pressure connections to the pilot cylinder 70, the control valve 94, and to the actuating cylinder 120 will be the reverse of that previously described and shown in FIGURE 1. Oil under pressure, which passes through pressure regulator valve 30 will then flow through branch pipe 32 into pilot valve inlet port connection 34, through valve passage 244, out at pilot valve port connection 82, and through pipe 78 into the left hand end 74 of pilot cylinder 70, and the right hand inner end 76 of pilot cylinder 70 will at the same time be connected through pipe 80 to the pilot valve port connection 84, through valve passage 242, out of pilot valve port connection 52, and through pipe 54 to the return lines 49 and 50, and thence to the oil reservoir 10. Under the latter conditions, the piston 72 in the pilot cylinder 70 will be immediately forced into its extreme right hand position, as shown in FIGURE 2, and will like-wise position the valve spools 62, 64, and 66 also in their most right hand position within the bore 60 of the control valve 44. With the valve spools 62, 64, and 66 of the control valve 44 thus positioned, oil under pressure can then flow through the pressure regulator valve 30 and branch pipe 40, into control valve pressure inlet 42, through control valve inlet port 96, through the interval immediate the valve spools 62 and 64 to the port 92, and thence out through pipe 102 and into connection 106, through passage 110 into the left hand end 114 of the actuating cylinder 120. The opposite right hand end 116 of the actuating cylinder 120 is at the same time put in exhaust communication with the oil reservoir return lines 49 and 50 by way of the passage 112 in the end of actuating cylinder 120, out through connection 108, through pipe 104, and into port 94 of the control valve 44, and thence through the interval between the valve spools 64 and 66 to the exhaust port 90 and from there out through the exhaust manifold passage 100 and pipe 48 to the before mentioned return lines 49 and 50.

Under the latter conditions, the differential pressure applied across the piston 122 of the actuating cylinder 120 is such as to tend to move it in a right hand direction, as indicated by the arrow 119, as viewed in FIGURE 2. Such motion will be intermittent and at a relatively slow rate depending upon the occurrence, frequency, and rate of demand of coating composition from the pressurizing cylinder 130, as controlled by the spray device 200. When such latter motion occurs, the piston rods 123 and 134, the coupling 138, and the flange 220 carried thereby are likewise moved in a right hand direction until

the flange 220 engages the stop 228 of the slide sleeve 224, and the slide sleeve 224 and the arm 232 carried thereby are moved in a right hand direction until the extreme right hand position thereof has been reached, as shown in FIGURE 1, and the position of the plug portion 240 of the pilot valve 36 and other conditions initially described are thereby reestablished.

Thus, as and when the pistons 122 and 132 move together between their extreme right hand and left hand positions within the cylinders 120 and 130, the plug of the pilot valve is correspondingly rotationally moving back and forth between the valving positions illustrated in FIGURES 1 and 2 and in enlarged detail in FIGURE 3, thereby valving the actuating oil alternately to opposite sides of the piston 122 in opposite ends of the actuating cylinder 120, and thereby causing reciprocating movement of the piston 132 in the pressurizing cylinder 130.

The coating composition feed and circulating pump 152 is driven by the engine 260, and withdraws coating composition from the container 166 through the suction hose 160, filter 158, pump inlet pipe 156, and pump inlet connection 154, and discharges the coating composition from the pump outlet connection 163, through pipes 170 and 180, relief valve 182, pipe 184, and flexible hose 186 to the container 166. Normally, feed pump 152 is run at a rate, and valve 182 adjusted, such that the coating composition is circulated to and from the container 166 through the pump 152 at a rate which is several times greater than the maximum demand for the spraying operation. The relief valve 182 is adjusted such as normally to result in a back pressure in feed line 170 of approximately 50 lbs. per square inch or whatever is required, depending upon the kind and character of coating composition being utilized, for adequate supply thereof to the pressurizing cylinder 130.

Assuming that the piston 132 in the cylinder 130 is being urged in the left hand direction indicated by arrow 118, as shown in FIGURE 1, the coating composition under pressure flows or tends to flow from the coating composition feed pump 152 through feed line 170, and thence through check valve 174, pump manifold pipe 178, to the inlet connection 159 at the right hand end of the cylinder 130, and thence in through the head passage 146 into the right hand end of the cylinder 142. At the same time, pressure is applied by the action of the actuating cylinder, to the coating composition already present in the left hand end 140 of the cylinder 130, which tends to force it out through the cylinder head passage 144, connection 148, and thence through check valve 190, pipe 194, hose connection 196, and through the flexible hose 198 to the spray gun 200. Upon intermittent actuation of the valve in the spray gun 200, with the resultant intermittent release of coating composition from the nozzle, the pressurizing piston 132, and consequently the actuating piston 122 are thereby correspondingly released for intermittent movement, the effective rate and distance of such resultant increments of movement being dependent upon the time and frequency of such intermittent operation of the spray gun 200.

When the piston 132 has reached the limit of its left hand stroke in cylinder 130, the valving mechanism is actuated, as before described, such as to cause the piston 132 to be urged to move toward the right hand end of the cylinder 120, and piston 132 likewise to be urged toward the right hand end of cylinder 130, and such motion will then result in coating composition under pressure in the supply line 170 from the feed pump 152, flowing or tending to flow through the check valve 172, manifold connection 176, into cylinder inlet 148, through cylinder passage 144, and thence into the space 140 in the left hand end of the cylinder 130. Meanwhile, while piston 132 is urged toward the right hand end of the cylinder 130, as before mentioned, pressure is thereby applied to the coating composition in the space 142 in the right hand end of cylinder 130, which tends to force

it to flow out through the cylinder passage 146, cylinder connection 140, through manifold pipe 178, check valve 192 and pipe 194, to the hose connection 196, and thence through the flexible hose 190 to the spray gun 200.

5 The before mentioned reciprocative or axial movements of piston 132 will, of course, only occur when and for so long as there is demand for coating composition at the spray gun 200 resulting from opening of the spray gun valve by means of manipulation of the valve trigger 203 in a manner well known in the art. When there is 10 no demand for coating composition at the spray gun 200, the coating composition continues to be continuously recycled and circulated by means of the feed pump 152 to and from the coating composition container 166, as hereinbefore mentioned, but the pistons 122 and 132 will 15 remain stationary in cylinders 120 and 130. The accumulator 204, which is connected through pipe 202 to the coating composition supply pressure pipe 194, entraps a body of air in the top thereof, and such air being at the 20 average pressure of the coating composition being supplied, serves as a cushion or pressure reserve to make it possible to meet the sudden demands of the spray gun 200.

With the pistons 122 and 132 having equal diameters, 25 as shown in the drawings, the pressure maintained by the system in the coating composition lines leading to the spray gun 200 will be approximately equal to the pressure of the oil supplied from the oil pump 12 through the line 20, as indicated by the pressure gauge 47 and as modified by pressure regulator 30, plus the pressure of the coating composition from feed pump 152, except for frictional losses in the system mainly in the actuating cylinder 120 and the pressurizing cylinder 130. However, the oil in the pressurizing and circulating system need 30 not necessarily be equal to the coating composition pressure in the coating composition circulating system, but the relation therebetween may be made any desired value depending upon the ratio of the diameter of piston 122 to the actuating cylinder 120 and piston 132 in the pressurizing cylinder 130.

35 An important advantage and feature of the pumping system, as hereinbefore described, resides in its operating characteristics, made possible by its novel pressurizing, feeding, and valving arrangement, which precludes the occurrence of any appreciable intervals of pressure drop or so-called dead center effects between pressurizing strokes of the piston pump. Thus, a substantially constant pressure is always maintained and available at the spray gun regardless of the rate and frequency of spraying operation. In normal operations, a pressure of the order of 2000 lbs. per square inch is maintained in the coating composition feed leading to the spray gun.

40 Specific apparatus, which has been found suitable for use as the principal components of the hereinbefore described apparatus are as follows. For the pilot valve, shown at 36 in the drawings, a Rotary Pilot Valve, Model No. 228-A manufactured by the Hydraulic Power Division of The Hydraullic Press Mfg. Co., Mount Gilead, Ohio. For the four-way control valve, shown at 44 in the drawings, a Four-Way Valve, Model 2200-A-3/8" manufactured by Hydraulic Power Division of The Hydraullic Press Mfg. Co., Mount Gilead, Ohio. For both the actuating cylinders, shown at 120 in the drawings, and the pressurizing cylinder, shown at 130 in the drawings, a 3 1/4 bore by 4" stroke Heavy Duty Hydraulic Cylinder, manufactured by Atlas Division of Sawyer Machine Works, Eugene, Oregon. For the oil pump, shown at 12 in the drawings, a Hydraulic Piston Pump, Cat. No. PF 3003-11, manufactured by Dynex, Inc., Pewaukee, Wisconsin. For the coating composition feed pump, shown at 152 in the drawings, a B & S No. 2-S rotary gear pump, manufactured by Brown & Sharp Mfg. Co., Providence, Rhode Island. For the pressure oil unloading valve, shown at 56 in the drawings, an Unloading Valve Part No. 62005-8 SAE manufactured by Fluid

Controls, Inc., Mentor, Ohio. For the paint supply bypass valve, shown at 182 in the drawings, a $\frac{3}{8}$ " Relief Valve manufactured by Brown & Sharp Mfg. Co., Providence, Rhode Island. For the pressure reducing and regulating valve, shown at 30 in the drawings, a Pressure Reducing Valve, Model No. 2300 manufactured by Hydraulic Power Division of The Hydraulic Press Mfg. Co., Mount Gilead, Ohio. For each of the check valves, shown at 172, 174, 190, and 192 in the drawings, a Pneu-Trol Check Valve No. 3000- $\frac{1}{2}$ " manufactured by Auto-Ponents, Inc., Belwood, Illinois. For the oil filter, shown at 16 in the drawings, a Suction Line Filter, Model No. 5 M 75 manufactured by Capital Engineering & Mfg. Co., Chicago, Illinois. The spray gun, shown at 200 in the drawings, may be any one of a number of suitable and well known components which may be purchased on the open market.

While the preferred embodiment of the invention has been herein disclosed, it is to be understood that the particular embodiment of the invention herein described, and shown in the drawings, is merely illustrative and not restrictive of the broad invention, and that many changes in design, structure, and arrangement may be made by those skilled in the art without departing from the scope of the invention, as defined in the appended claims.

What is claimed is:

1. In a coating composition pressurizing and spraying system, apparatus comprising:
  - a pump means including means for withdrawing actuating fluid from a reservoir containing actuating fluid and for discharging same therefrom under pressure through a first discharge means;
  - means for receiving coating composition from a container and conveying same under a given pressure to a pressurizing inlet means;
  - pressurizing means for receiving coating composition from said pressurizing inlet means at said given pressure and simultaneously discharging same through a second discharge means at an increased pressure, said pressurizing means including:
    - a pressurizing cylinder,
    - a pressurizing piston reciprocably contained in said pressurizing cylinder;
  - actuating means operative by actuating fluid received thereby under pressure from said first discharge means of said pump means for actuating said pressurizing means,
  - said actuating means including:
    - an actuating cylinder,
    - an actuating piston reciprocably contained in said actuating cylinder,
    - said pressurizing and actuating pistons being interconnected by a common means for simultaneous reciprocating movement respectively in said pressurizing cylinder and actuating cylinder;
  - pilot valve means;
  - control means actuated by said pistons, including lost motion means, for shifting said pilot valve means to opposite positions only adjacent the end of each opposite reciprocative travel of said pistons;
  - control valve means responsive to said shift of said pilot valve means for complete movement to opposite valving positions upon each said opposite shift of said pilot valve means, said pilot valve including means for receiving actuating fluid under pressure from said first discharge means and when in one such shifted position thereof admitting such actuating fluid under pressure to a first end of said actuating cylinder to urge said actuating piston to move in a direction therein toward the second end thereof, while permitting discharge of actuating fluid from the second end of said actuating cylinder to such reservoir, and when in the opposite such shifted posi-

tion admitting such actuating fluid under pressure to said second end of said actuating cylinder to urge said actuating piston to move in a direction therein toward the first end thereof, while permitting discharge of actuating fluid from said first end of said actuating cylinder to such reservoir;

means including valve means operative in connection with said pressurizing cylinder for admitting coating composition from said pressurizing inlet means to a first end of said pressurizing cylinder, and for simultaneously discharging coating composition under pressure from the second end of said pressurizing cylinder to said second discharge means when said actuating piston and thereby said pressurizing piston is being urged in one direction, therein; and for admitting coating composition from said pressurizing inlet means to said second end of said pressurizing cylinder, and for simultaneously discharging coating composition under pressure from said first end of said pressurizing cylinder to said second discharge means when said actuating piston and thereby said pressurizing piston is being urged in the other direction therein,

the movement of said pressurizing piston and consequently the movement of said actuating piston being controlled by and occurring only upon discharge of coating composition from said second discharge means,

and means for connecting coating composition release and spray forming means to said second discharge means.

2. In a coating composition pressurizing and spraying system, apparatus comprising:
  - a pump means including means for withdrawing actuating fluid from a reservoir containing actuating fluid and discharging the same therefrom under a first pressure through a first discharge means;
  - means for maintaining said first discharge pressure substantially constant;
  - means for receiving coating composition from a container and conveying same to a pressurizing inlet connection means;
  - pressurizing means for receiving said coating composition through said inlet connection means and for discharging same through a second discharge means at increased pressure;
  - said pressurizing means including:
    - a pressurizing cylinder,
    - a pressurizing piston reciprocably contained in said pressurizing cylinder,
  - and actuating means operative by actuating fluid received thereby under pressure from said first discharge means of said pump means;
  - said actuating means including:
    - an actuating cylinder,
    - an actuating piston reciprocably contained in said actuating cylinder,
    - said pressurizing and actuating pistons being interconnected by a common means for simultaneous reciprocating movement respectively in said pressurizing cylinder and actuating cylinder;
  - pilot valve means;
  - control means actuated by said pistons including lost motion means, for shifting said pilot valve means to opposite positions only adjacent the end of each opposite reciprocated travel of said pistons;
  - control valve responsive to said shift of said pilot valve means for complete movement to opposite valving positions upon each of said opposite shift of said pilot valve means, said pilot valve including means for receiving actuating fluid under pressure from said first discharge means and when in one such shifted position thereof admitting such actuating fluid under pressure to a first end of said actuating cylinder to urge said actuating piston to move in a direction

therein toward the second end thereof, while permitting discharge of actuating fluid from the second end of said actuating cylinder to such reservoir, and when in the opposite such shifted position admitting such actuating fluid under pressure to said second end of said actuating cylinder to urge said actuating piston to move in a direction therein toward the first end thereof, while permitting discharge of actuating fluid from said first end of said actuating cylinder to such reservoir;

means including valve means operative in connection with said pressurizing cylinder for admitting coating composition through said inlet connection means to a first end of said pressurizing cylinder, and for simultaneously discharging coating composition under pressure from the second end of said pressurizing cylinder to said second discharge means when said actuating piston and pressurizing piston is being urged in one direction, as aforesaid, and for admitting coating composition through said inlet connection means to said second end of said pressurizing cylinder, and for simultaneously discharging coating composition under pressure from said first end of said pressurizing cylinder to said second discharge means when said actuating piston and pressurizing piston are being urged in the other direction, as aforesaid;

the movement of said pressurizing piston and consequently the movement of said actuating piston thereby being effected by both the pressure of the actuating fluid and the pressure of the coating composition, and being controlled by and occurring only upon discharge of coating composition from said second discharge means,

and means for connecting coating composition release and spray forming means to said second discharge means.

3. In a coating composition pressurizing and spraying system, apparatus comprising:

a pump means including means for withdrawing actuating fluid from a reservoir containing actuating fluid and for discharging same therefrom under pressure through a first discharge means;

means for receiving coating composition from a container and conveying same to a pressurizing inlet means;

pressurizing means for receiving coating composition from said pressurizing inlet means and simultaneously discharging same through a second discharge means at an increased pressure,

said pressurizing means including:

a pressurizing cylinder,

a pressurizing piston reciprocably contained in said pressurizing cylinder,

actuating means operative by actuating fluid received thereby under pressure from said first discharge means of said pump means for actuating said pressurizing means,

said actuating means including:

an actuating cylinder,

an actuating piston reciprocably contained in said actuating cylinder,

said pressurizing and actuating pistons being interconnected by a common means for simultaneous

reciprocating movement respectively in said pressurizing cylinder and actuating cylinder;

control valve means actuated by said pistons including lost motion means, for shifting said valve means to opposite positions only adjacent the end of each opposite reciprocative travel of said pistons, said control valve including means for receiving actuating fluid under pressure from said first discharge means and when in one such shifted position thereof admitting such actuating fluid under pressure to a first end of said actuating cylinder to urge said actuating

piston to move in a direction therein toward the second end thereof, while permitting discharge of actuating fluid from the second end of said actuating cylinder to such reservoir, and when in the opposite such shifted position admitting such actuating fluid under pressure to said second end of said actuating cylinder to urge said actuating piston to move in a direction therein toward the first end thereof, while permitting discharge of actuating fluid from said first end of said actuating cylinder to such reservoir;

means including valve means operative in connection with said pressurizing cylinder for admitting coating composition from said pressurizing inlet means to a first end of said pressurizing cylinder, and for simultaneously discharging coating composition under pressure from the second end of said pressurizing cylinder to said second discharge means when said actuating piston and thereby said pressurizing piston is being urged in one direction, therein;

and for admitting coating composition from said pressurizing inlet means to said second end of said pressurizing cylinder, and for simultaneously discharging coating composition under pressure from said first end of said pressurizing cylinder to said second discharge means when said actuating piston and thereby said pressurizing piston is being urged in the other direction therein,

the movement of said pressurizing piston and consequently the movement of said actuating piston being controlled by and occurring only upon discharge of coating composition from said second discharge means,

and means for connecting coating composition release and spray forming means to said second discharge means.

4. In a coating composition pressurizing and spraying system, apparatus comprising:

a first pump means for receiving fluid from a reservoir and discharging same at a first predetermined increased pressure;

a second pump means for receiving coating composition from a container and discharging same at a second predetermined increased pressure;

pressurizing means, connected to said first pump means and actuatable by said fluid discharged therefrom, for receiving said coating composition from said second pump means under said second predetermined pressure and simultaneously discharging said coating composition through discharge means at a third predetermined pressure greater than said second predetermined pressure;

and means for connecting spray forming means to said discharge means.

5. In a coating composition pressurizing and spraying system, apparatus comprising:

a first pump means for receiving fluid from a reservoir and discharging same at a first predetermined increased pressure;

a second pump means for receiving coating composition from a container and discharging same at a second predetermined increased pressure;

pressurizing means, connected to said first pump means and actuatable by said fluid discharged therefrom, for receiving said coating composition from said second pump means under said second predetermined pressure and simultaneously discharging said coating composition through discharge means at a third predetermined pressure greater than said second predetermined pressure;

means for circulating coating composition from such container through said second pump means and return to such container at a rate greater than that at which said pressurizing means receives coating composition from said second pump means;

and means for connecting spray forming means to said discharge means.

6. In a coating composition pressurizing and spraying system, apparatus comprising:
- a fluid reservoir;
- a first pump means including means for receiving fluid from said reservoir and discharging same therefrom through a first discharge means;
- 5 unloading valve means interconnecting said first discharge means and said reservoir for bypassing fluid from said first discharge means to said reservoir when the fluid pressure in said first discharge means exceeds a first predetermined value;
- a second pump means, including means for receiving coating composition from a container and discharging same through a second discharge means;
- 10 unloading valve means for interconnecting said second discharge means and such container for circulating coating composition from such container through said second pump means and return to such container when the coating composition in said second discharge means reaches a second predetermined pressure;
- 15 pressurizing means actuatable by said fluid discharged from said first pump means, for receiving said coating composition from said second pump means through said second discharge means and simultaneously discharging same through a third discharge means at a final pressure greater than said second predetermined pressure;
- 20 and means for connecting spray forming means to said third discharge means.
7. In a coating composition pressurizing and spraying system, apparatus comprising:
- an actuating fluid reservoir;
- a first pump means for withdrawing actuating fluid from said reservoir and discharging same therefrom under pressure through a first discharge means;
- 30 adjustable unloading valve means interconnecting said first discharge means and said reservoir for bypassing actuating fluid from said first discharge means to said reservoir when the actuating fluid pressure in said first discharge means exceeds a first predetermined value;
- a second pump means, including means for receiving coating composition from a container and discharging same through a second discharge means;
- 35 adjustable unloading valve means for interconnecting said second discharge means and such container for continuously circulating coating composition through said second pump means and such container when the coating composition in said second discharge means reaches a second predetermined pressure;
- 40 pressurizing means for receiving said coating composition from said second pump means through said second discharge means at said predetermined pressure and simultaneously discharging same through a third discharge means;
- 45 actuating means operative by actuating fluid received thereby under pressure from said first discharge means of said first pump means for actuating said pressurizing means;
- 50 regulator means intermediate said first discharge means and said actuating means for maintaining the said actuating fluid received by said actuating means from said first discharge means at substantially a constant predetermined pressure, thereby maintaining coating composition in said third discharge means likewise at a substantially constant predetermined pressure;
- 55 and means for connecting means to said third discharge means for releasing coating composition therefrom in the form of a spray.
8. In a coating composition pressurizing and spraying system, apparatus comprising:
- 70 a first pump means including means for withdrawing actuating fluid from a reservoir containing actuating fluid and discharging same therefrom under pressure through a first discharge means;

- a second pump means including means for receiving coating composition from a container and discharging same under increased pressure to a second discharge means;
- pressurizing means for receiving said coating composition from said second pump means through said second discharge means at said increased pressure and discharging same through a third discharge means;
- said pressurizing means including:
- a pressurizing cylinder,
- a pressurizing piston reciprocably contained in said pressurizing cylinder;
- actuating means operative by actuating fluid received thereby under pressure from said first discharge means of said first pump means for actuating said pressurizing means;
- said actuating means including:
- an actuating cylinder,
- an actuating piston reciprocably contained in said actuating cylinder,
- said pressurizing and actuating pistons being interconnected by a common piston rod means for simultaneous reciprocating movement respectively in said pressurizing cylinder and actuating cylinder;
- pilot valve means;
- control means actuated by said piston rod means, including lost motion means, for shifting said pilot valve means to opposite positions only adjacent the end of each opposite reciprocative travel of said piston rod means;
- control valve means responsive to said shift of said pilot valve means for complete movement to opposite valving positions upon each said opposite shift of said pilot valve means, said pilot valve including means for receiving actuating fluid under pressure from said first discharge means and when in one such shifted position thereof admitting such actuating fluid under pressure to a first end of said actuating cylinder to urge said actuating piston to move in a direction therein toward the second end thereof, while permitting discharge of actuating fluid from the second end of said actuating cylinder to such reservoir, and when in the opposite such shifted position admitting such actuating fluid under pressure to said second end of said actuating cylinder to urge said actuating piston to move in a direction therein toward the first end thereof, while permitting discharge of actuating fluid from said first end of said actuating cylinder to such reservoir;
- means including valve means operative in connection with said pressurizing cylinder for admitting coating composition under said increased pressure from said third discharge means to a first end of said pressurizing cylinder, whereby said pressurizing piston is urged to move in said pressurizing cylinder toward the second end thereof, and for discharging coating composition under pressure from the second end of said pressurizing cylinder to said third discharge means when said actuating piston and thereby said pressurizing piston is being urged in one direction, as aforesaid;
- and for admitting coating composition from said third discharge means to said second end of said pressurizing cylinder whereby said pressurizing piston is urged to move in said pressurizing cylinder toward said first end thereof, and for discharging coating composition under pressure from said first end of said pressurizing cylinder to said third discharge means when said actuating piston and thereby said pressurizing piston is being urged in the other direction,
- the movement of said pressurizing piston and consequently the movement of said actuating piston

being controlled by and occurring only upon discharge of coating composition from said third discharge means,
and means for connecting coating composition release and spray forming means to said third discharge means. 5

9. In a coating composition pressurizing and spraying system, apparatus comprising:
- a first pump means including means for withdrawing actuating fluid from a reservoir containing actuating fluid and discharging the same therefrom under pressure through a first discharge means; 10
  - adjustable unloading valve means including means for interconnecting said first discharge means and such reservoir for bypassing actuating fluid from said first discharge means to said reservoir when the actuating fluid pressure in said first discharge means exceeds a first predetermined value; 15
  - a second pump means including means for receiving coating composition from a container and discharging same under increased pressure to a second discharge means; 20
  - adjustable unloading valve means interconnecting said second discharge means and such container for continuously circulating coating composition through said second pump means and such container when the coating composition in said second discharge means reaches a second predetermined pressure; 25
  - pressurizing means for receiving said coating composition from said second pump means through said second discharge means at said predetermined pressure and discharging same through a third discharge means; 30
  - said pressurizing means including:
    - a pressurizing cylinder, 35
    - a pressurizing piston reciprocably contained in said pressurizing cylinder, and
    - actuating means operative by actuating fluid received thereby under pressure from said first discharge means of said first pump means for actuating said pressurizing means; 40 - said actuating means including:
    - an actuating cylinder,
    - an actuating piston reciprocably contained in said actuating cylinder, 45
    - said pressurizing and actuating pistons being interconnected by a common piston rod means for simultaneous reciprocating movement respectively in said pressurizing cylinder and actuating cylinder;
    - pilot valve means;
    - control means actuated by said piston rod means including lost motion means, for shifting said pilot valve means to opposite positions only adjacent the end of each opposite reciprocated travel of said piston rod means; 55
    - control valve means responsive to said shift of said pilot valve means for complete movement to opposite valving positions upon each of said opposite shift of said pilot valve means, said pilot valve including means for receiving actuating fluid under pressure from said first discharge means and when in one such shifted position thereof admitting such actuating fluid under pressure to a first end of said actuating cylinder to urge said actuating piston to move in a direction therein toward the second end thereof, while permitting discharge of actuating fluid from the second end of said actuating cylinder to such reservoir, 60
    - means for connecting coating composition release and spray forming means to said third discharge means when in the opposite such shifted position permitting such actuating fluid under pressure to said second end of said actuating cylinder to urge said actuating piston to move in a direction therein toward the first end thereof, while permitting discharge of actuating fluid from said first end of said actuating cylinder to such reservoir; 65

and when in the opposite such shifted position permitting such actuating fluid under pressure to said second end of said actuating cylinder to urge said actuating piston to move in a direction therein toward the first end thereof, while permitting discharge of actuating fluid from said first end of said actuating cylinder to such reservoir; means including valve means operative in connection with said pressurizing cylinder for admitting coating composition under said increased pressure from said third discharge means to a first end of said pressurizing cylinder, whereby said pressurizing piston is urged by said coating composition pressure to move in said pressurizing cylinder toward the second end thereof, and for discharging coating composition under pressure from the second end of said pressurizing cylinder to said third discharge means when said actuating piston and pressurizing piston is being urged in one direction, as aforesaid; and for admitting coating composition from said third discharge means to said second end of said pressurizing cylinder, whereby said pressurizing piston is urged to move in said pressurizing cylinder toward said first end thereof, and for discharging coating composition under pressure from said first end of said pressurizing cylinder to said third discharge means when said actuating piston and pressurizing piston are being urged in the other direction, as aforesaid; the movement of said pressurizing piston and consequently the movement of said actuating piston thereby being caused by both the pressure of the actuating fluid and the pressure of the coating composition, and being controlled by and occurring only upon discharge of coating composition from said third discharge means, and means for connecting coating composition release and spray forming means to said third discharge means.

10. Apparatus in accordance with claim 9 and regulator means intermediate said first discharge means and said actuating means for maintaining said actuating fluid received by said actuating means at substantially a constant predetermined pressure, thereby maintaining coating composition in said third discharge means likewise at a substantially constant predetermined pressure.

11. Apparatus in accordance with claim 9 and regulator means intermediate said first discharge means and said actuating means for maintaining said actuating fluid received by said actuating means at substantially a constant predetermined pressure, and regulator means in said second discharge means for maintaining said coating composition received by said pressurizing cylinder at substantially constant predetermined pressure, thereby maintaining coating composition in said third discharge means likewise at a substantially constant predetermined pressure.
